WITNESS:

G. H. Gillespie,
INVENTOR
Victor J. Evans

ATTORNEY

UNITED STATES PATENT OFFICE.

GUS H. GILLESPIE, OF LEXINGTON, KENTUCKY.

LOADING DEVICE.

Application filed September 29, 1926. Serial No. 138,482.

This invention relates to a loading device, the general object of the invention being to provide a car and an inclined track for moving articles from one level to a higher level 5 or vice versa, the car being so formed that its supporting surface will be horizontal while it rests on the inclined track.

Another object of the invention is to provide an adjustable platform for receiving 10 the articles from the car, with means for pulling the track toward the platform as the platform is raised.

This invention also consists in certain 15 other features of construction and in the combination and arrangement of the several parts, to be hereinafter fully described, illustrated in the accompanying drawings and specifically pointed out in the appended claims.

20 In describing my invention in detail, reference will be had to the accompanying drawings wherein like characters denote like or corresponding parts throughout the several views, and in which:—

25 Figure 1 is an elevation of the invention. Figure 2 is a plan view thereof.

Figure 3 is a longitudinal sectional view.

Figure 4 is a side view of the platform.

In these views, A indicates the inclined 30 track, B the carriage or car thereof and C indicates the platform for receiving the articles from the carriage or car. The track A is composed of the beams 1 which have their lower ends cut off at an angle, as

35 shown at 2, and their upper ends rounded, as at 3. The beams are connected together by the cross pieces 4. A shaft 5 is journaled in the lower end of the track and carries the arms 6 which are provided with the rollers

40 7. A handle 8 is connected with the shaft 5 so that it can be rocked. When this shaft is rocked forwardly, the arms 6 will swing downwardly, bringing the rollers 7 in engagement with the surface upon which the 45 track rests, thereby raising the lower end of the track above the surface, so that the track can be moved.

The car or carriage B comprises a lower frame 9 which is provided with the rear 50 wheels 10 and the front wheels 11, these wheels engaging the beams 1 of the track. The front wheels are of less diameter than the rear wheels, as shown. A body 12, having an inclined upper edge, is hinged at its front end to the front of the frame 9, as shown at 13. Legs 14 are pivoted to the

rear part of the body and engage a part of the frame 9 and a block 15 is arranged at the rear of the body and forms a chock for articles placed on the body. It will be seen 60 that when the legs 14 engage a part of the frame 9, the upper edge of the body will be in a horizontal position, the small front wheels enabling the parts to assume this position without making the legs 14 of considerable length. These legs can be folded upwardly so that the body will rest upon the frame, thereby decreasing the height of the carriage.

A cable 16 is connected with the carriage 70 and after passing over a pulley 17 on a cross piece at the upper end of the track, extends downwardly and is connected to a drum 18 carried by a shaft 19 journaled in the track. The shaft 19 is connected by 75 the gears 20 with a shaft 21 which is adapted to be driven by a motor 22 through means of the worm gearing 23. A handle 24 is adapted to operate the clutch means 25 to disconnect the shaft 19 from the shaft 21, 80 whenever desired, so as to free the drum or shaft from the motor shaft. When the shaft 19 is driven from the motor, the drum will wind the cable thereon so as to pull the carriage up the track.

The table or platform C is formed of a base section 26 which is supported by the caster wheels 27 and the top section 28 which has sliding movement in the bottom section. The top section supports a turntable 29 90 which is provided with the anti-friction means 30. The top section 28 is provided with the racks 31 and toothed wheels 32 engage the racks, the wheels being carried by the shafts 33 journaled in the base section 95 and each shaft being provided with a handle 34.

A cable 35 is connected with the track A and passes over a guiding pulley 36 on the base section and has its upper end connected 100 with a brace 37 on the upper section. Thus when the upper section is raised, the cable is pulled upon and thus the track section will be moved toward the table or platform so that its upper end will remain in engagement with the upper end of the top section.

This device is mainly intended for racking hogsheads in a warehouse where the hogsheads are placed in rows with aisles between them. By making the car adjustable as to height, it can be lowered when a barrel or hogshead is to be placed on another

row of barrels and then when another barrel is to be placed on the second row, the car is raised so that the barrel will be supported in a position where it can be placed on the second row. The platform will enable a barrel or hogshead to be placed thereon from the car, and then by turning the platform, the barrel can be rolled off on to a pile of barrels.

10. It is thought from the foregoing description that the advantages and novel features of my invention will be readily apparent.

I desire it to be understood that I may make changes in the construction and in the 15 combination and arrangement of the several parts, provided that such changes fall within the scope of the appended claims.

What I claim is:—

1. An apparatus of the class described 20 comprising a platform having an upper and lower part, its upper part being telescopically connected with the lower part, rack means

for lowering and raising the upper part, an inclined track having its upper end resting upon the platform, a cable connecting the 25 upper portion of the platform with the track, a shaft arranged adjacent the lower end of the track, arms carried by the shaft, a wheel carried by each arm and means for swinging the shaft to move the arms into position where the wheels will engage the surface upon which the device rests.

2. A loading device comprising a track, a platform composed of an upper and lower section, means for adjusting the upper section vertically, the upper end of the track resting against the upper end of the platform, wheels on the lower end of the track and a cable connecting the track to the upper 35 section of the platform so that the track will be moved when said section is elevated.

In testimony whereof I affix my signature.

GUS H. GILLESPIE.
